METHOD OF COVERING BALLS

Fred Thomas Roberts, Ridgefield, Conn.

Application May 3, 1945, Serial No. 591,787

9 Claims. (Cl. 154—16)

1

This invention relates to a system of covering tennis and like balls. Heretofore it has been the custom to apply manually two 8-shaped covers cemented to the exterior of a previously formed and inflated ball, the edges of the two cover members adjoining. An object of my invention is to reduce the manual operation to a minimum, and cover the ball more accurately and at less expense.

Most tennis balls are first made as a completed rubber ball, molded and inflated to the correct size for covering, and then the covers of melton are attached by hand, the covers being first cut in the conventional figure 8 pieces. These figure 8 covers are usually died out of a layer of melton, to one face of which cement has been previously applied, and are then stacked together and the edges cemented while in the stack. They are then separated and attached to the surface of the ball by hand. Great skill is required to get the covers on straight and without wrinkles, and the edges are cemented together with the cement previously put on the pieces while they were stacked together.

Due to the fact that the ball, covered as above described, is then given a vulcanization to set the cement, there is a shrinkage of the melton cover, so an allowance is made for this shrinkage, the cover being cut with a fullness, and this adds to the difficulty of properly applying the covers and joining their edges.

In ordinary practice, the balls after being in this manner covered are put in a mold having cavities of the correct size, the mold closed and vulcanizing heat applied, the heat generating enough additional pressure so that the cover is ironed out smoothly.

The heat and pressure usually employed mats the wool fibers down on the ball, and it is necessary to resort to additional operations to fluff up the material, which is usually done by tumbling the balls in live steam after they are completed. In my process, I am able to use air-curing to vulcanize the cover in place and thereby eliminate this subsequent step.

My process, which is partly manual and partly mechanical, is hereinafter more fully described in connection with the accompanying drawings, and the different steps in process fully explained.

In the drawings, Fig. 1 is a view illustrating an inflated ball to be covered; Fig. 2 is a plan of one of the two sections of the cover; Fig. 3 is a view of the ball with the cover preliminarily placed thereon; Fig. 4 is a plan partly broken away of one of the molding members; Fig. 5 is

2

a section separated and partly broken away through the two members of the cover applying mold, the plane of the section being indicated by the line 5—5 on Fig. 4; Fig. 6 is an enlarged fragmentary section of cooperating portions of the two mold members, a vacuum having been applied to draw the rubber sheathing into the mold cavities; Fig. 7 is a fragmentary section similar to Fig. 6 but illustrating the preliminarily covered ball placed in the cavity and the mold members brought together; Fig. 8 is a view similar to Fig. 7 illustrating the result after the application of a vacuum to the space between the ball and the cover, the ball having expanded gradually from its internal pressure to fill the cavity, causing the cover to be molded into place on the ball; Fig. 9 is a view similar to Fig. 8 but illustrates the application of a fluid pressure to the space between the sheaths and the mold cavities while maintaining the vacuum between the ball and the sheath, this view presses the cover onto the ball; Fig. 10 is a detail in section through one of the mold cavities showing the effect when the mold members are separated and the pressure and vacuum released; Fig. 11 is a view of the covered ball as released from the mold showing the application of a filling strip to the space between the cover sections; Fig. 12 is a cross section of the filling strip, as indicated by the line 12—12 on Fig. 11 but on a larger scale.

In carrying out my process I cover one face of a number of layers of melton with air-curing cement. This is a cement which closes the pores of the melton on that side and becomes substantially dry in place but is able to effect a ready adherence of the cover to a ball covered with cement of a different character. Out of the cement covered layer I cut, with a die, conventional figure 8 pieces as shown at A in Fig. 2. I then stack the figure 8 pieces one above the other with their edges in alignment and apply air curing cement to such cut edges in the usual manner.

I take a center comprising a hollow rubber ball B, Fig. 1, which is inflated by an internal fluid pressure to the degree desired in the finished ball, for instance, 42 pounds to the square inch for a tennis ball. This inflation may be effected by closing the ball in an atmosphere of compressed air, or by closing it with suitable chemicals in the interior which react to produce a pressure, or by puncturing the completed ball with a hypodermic needle and injecting compressed fluid, all of these practices being common in the art.

3

I now place two of the cover members A about the ball B covered with cement with the longitudinal axes of the cover pieces at right angles to each other, but instead of following the usual practice of pressing the cover down by hand throughout its width to the ball, I press it only along two narrow equatorial zones indicated at X—X and Y—Y on Fig. 3, taking care that the cover members outside of these zones are free from the ball.

I now place the ball with the two cover members preliminarily attached, as described, in a mold which is submitted to suction to exhaust the air from the space between the exterior of the ball and the interior of the cover members and about the exterior of the cover members. Thereupon the ball with its cover expands into contact with the mold surface by reason of the internal pressure in the ball and this causes the cover to tightly adhere to the ball center forming a perfect sphere smoothly covered.

In effecting the above operation, I prefer to use such mold members as shown in Figs. 4 to 10 inclusive, which I will now describe.

In Figs. 4 and 5, I show a pair of suitable plates 10, each having a number of mold cavities 11, of approximately hemispherical shape, five rows of five cavities each being indicated in these figures. Each cavity has a vent 12 at its bottom, connecting it with suitable conduits 14, which lead to a common conduit to which an exhausting hose 15 may be attached to exhaust all of the cavities.

Extending across all of the cavities in each mold member is a sheet of vulcanized rubber 16, held at its margin to the mold member. I have shown the marginal edges as being bent into a groove 17 surrounding the set of mold cavities and I place a suitable metal frame 18 in this groove, over the margins of the rubber sheet 16, and secure it by screws, one of which is shown at 19 in Fig. 10.

When the air is exhausted from the cavities of the mold through the conduit 15, the rubber sheet 16 becomes seated in each of the cavities forming a lining therefor, as indicated in Fig. 6. These members 10 with their rubber lined cavities constitute the mold in which I place the balls with the covers preliminarily attached as in Fig. 3, one of such balls being shown in Fig. 7 entrapped between the two mold members 10.

Before bringing the mold members together, I place an exhausting tube 20 in the region between them, the ends of such tube being clamped between the two rubber sheets 16 on the inner side of the annular securing members 18, as shown in Fig. 7. The cavities in each mold member are connected at the face of the mold by grooves 13 and the rubber sheet 16 sinks into these grooves thus providing a tubular connection between successive rubber lined cavities, as indicated in Fig. 8. The exhausting conduit 20 is thus in communication with each of the rubber lined cavities.

I now apply suction to the conduit 20 exhausting the air from all of the lined cavities so that the air is exhausted not only from outside the cover but from the unattached regions between the covers and ball. The exhaustion of this surrounding air in the cavities results in the internal pressure in the ball expanding it so that its cover comes snugly into engagement with the rubber wall of the cavity, as shown in Fig. 8. This forces the cover throughout its width snugly against the ball center and causes its adherence

4

while the exterior of the cover is maintained in smooth condition by the pressure against the lining of the cavity.

The action of exhausting the air between the marginal portions of the cover and the ball results in a firmer securing of the cover to the ball than in the usual hand operation, and the expansion of the ball by its internal pressure against the rubber lined cavities causes the exterior of the cover to be perfectly spherical and have a smooth exterior.

It is to be understood that the cement employed on the inner face of the cover and the exterior of the ball is of the so-called migratory character. That is to say, the cement on the cover is of one composition and the cement on the ball of a different composition and one of them needs to receive something from the other to enable it to acquire sufficient adhering characteristics. I use on the cover a cement which in itself will not become vulcanized rubber, as it has no vulcanizing agent in it. As the covers are not always immediately used after being coated with cement and cut into figure 8-shapes, the solvent will evaporate but the rubber will not become vulcanized and will remain sticky. The cement used on the ball has an excess of vulcanizing agent mixed in it and provides the amount required to vulcanize the rubber film left on the cover when it comes in contact with it. The result is that I handle both the cover and the ball, each with their applied cements, in a satisfactory manner, but when the cover is firmly pressed on the ball, the cements unite and become vulcanized and form an effective union.

If desired, to obtain a greater pressure in seating the cover than that furnished by the internal pressure of the ball itself, I may readily effect this by turning off the suction to the passageways 12 which have held the rubber lining in the mold and in place thereof supplying compressed air to such passageways which thereupon forces the lining positively against the exterior of the melton cover, pressing it with increased firmness against the ball.

I now open the conduit from the passages 12 so that the space between the bottoms of the cavities in the mold members 10 and rubber linings is open to the atmosphere, thus freeing the linings from the cavities. I then separate the mold members whereupon the entirely freed lining springs back by its own elasticity into its original planular condition supporting the balls above the cavities as shown in Fig. 10. This may complete the ball, or may complete it except for an 8 shaped groove C between the adjacent edges of the two cover members.

In attaching the cover to the ball there is an advantage in leaving a narrow space between the edges of the 8-shaped members, as it provides a channel adapted to receive excess of cement which is likely to accumulate on the edges of the 8-shaped pieces when they are stacked and cemented.

If no groove between the cover members is desired, I make the cover members of full size, so that their edges actually abut when they are in place on the ball, or a narrow groove may be left open between the applied covers if desired. I prefer, however, to leave a groove of substantial width as shown for instance at C in Figs. 8 to 11, and thereafter fill it by the application of a filling strip, as about to be described.

To fill the groove C, I may employ a rubber strip D cemented to both the ball center and

the edges of the covers. This strip is a longitudinally straight member but in cross section, is preferably formed as shown in Fig. 12. That is to say, it has a substantially flat bottom d , a grooved top portion d' and slightly inclined sides $d-2$. Such a member may be made by extrusion and coiled for use.

When such a strip, as shown, is placed in the groove C between the edges of the melton, the base d is firmly attached to the ball, the inclined edges $d-2$ abut and slightly underhang the edges of the cover, while the groove d' is on the exterior.

After this groove strip D has been placed in the groove between the cover members and pressed firmly into place, the ball is submitted to an air cure or other means of completing the vulcanization of the cement and thus the finished ball is produced. The groove d' in the applied strip gives to the finished ball the desired recess between the covers, familiar to tennis players, and is useful in preserving the accuracy of the ball as it moves through the air in response to the player's stroke.

In the old practice, when the ball was vulcanized against the surface of a metal mold, the cover surface would flatten down flush with the top of the cement in the groove between the covers and then after the surface was given a fluffing treatment to restore it the space above the exposed cement became an externally facing groove between the cover edges. Players have considered that this groove was an advantage in the ball, giving it a sort of rifling, causing it to follow more accurately the intended course, but when the fluff raised in the final treatment of the ball was worn down the groove ceased to exist and its rifling effect was lost, which some players claim results in the ball "floating" during play rather than following its true course. With my system of furnishing a seam groove extending lower than the normal surface of the covers independently of any temporary fluff thereof, I maintain the rifling groove effective for a much longer period than with the old hand method of manufacture.

My applied strip D gives the depressed seam mark desired by players but in a more regular and smoother form than where such depressed seam is bounded merely by the edges of the melton covering. Another advantage of my applied seam member is that it may, if desired, be of a contrasting color to the cover and thus furnish a useful identification mark for the user or trademark for the manufacturer.

In the usual method of applying covers by hand, the face and the edges of the covers are well covered with vulcanizable cement, so that the covers are rubberized at the edges and on one surface, and in applying such a cover to the surface of the ball in the ordinary method, there is great danger that air will be entrapped between the cover and ball and sealed therein by the adherence of the edges of the cover to the ball. This air remains in the ball and tends to loosen the cover in certain spots. By my method of withdrawing of the air from between the cover and the cemented surface of the ball while attaching the cover to the surface, covers are attached uniformly throughout, thus giving a more accurate ball and one with longer life.

By avoiding pressing the cover against a metal surface to smooth it as has been the custom heretofore, I maintain the cover with its original fluffed surface and I avoid the necessity for

subsequent treatment to fluff up the matted cover. It has not been practicable heretofore with a hand applied cover to employ air drying cement because it was necessary to iron out the roughly applied cover, and this was effected by using the usual vulcanizable cement and submitting the ball to this external hot ironing operation. With my method, however, of applying the covers no ironing operation is necessary and I may thus use an air curing cement and avoid the ironing operation altogether.

Of course, if desired, one could use my operation of exhausting the air between the cover and ball and employ vulcanizable cement and submit the completed ball to vulcanizing heat, but as such operation is unnecessary in my method, for the purpose of ironing out the cover, I prefer to avoid it altogether and thus avoid the necessity for subsequent treatment to fluff up the cover. There is also a saving in the melton by my method because the covers need not be cut with a fullness to allow for shrinkage which has heretofore resulted from the heat-vulcanization of the ball.

When the ordinary ball which requires vulcanization is to be covered by this apparatus and method, a cement requiring heat to vulcanize such cement is used both on the cover and the ball, as is now done in making the regular ball. When this method and apparatus is used to make the present type ball, there is gained by it efficiency in covering by eliminating the hand labor and there is the further advantage that the air is withdrawn from between the cover and the ball when the cover is attached and there will be no air pockets formed by trapping air between two rubber surfaces, as does often result in the ordinary joining of any two sheets of cemented material or rubberized surfaces.

I have referred to using cement of migratory character for uniting the cover to the ball. I find it satisfactory to use on the ball a cement containing butyl (which is a very strong accelerator) and for using on the cover a cement without butyl. There is sufficient butyl in the cement on the ball so that some of it passes to the cover as the cover comes in contact with the surface of the ball. I prefer to use enough cement on the ball so that some of it squeezes out beyond the edge portion of the covers as the ball is expanded by pressure over the entire surface, and this allows the covers to shift a little in the event that the cover accidentally adheres to the ball beyond the line of pressure made by the wheels.

The ball made by this entire method, using a cement to attach the cover that does not have to be vulcanized, and accurately positioning the covers on the ball and exhausting the air from between the covers and the cemented ball and swelling the ball against the covers, exerting additional pressure against the covers, if desired, and squeezing the ball back to the original size and carrying with it the cover, produces economically a very satisfactory ball. Such method avoids any wrinkling of the cover or trapping of air between the cover and the ball, and avoids the result of matting down the melton cover by heat and pressure during vulcanization and the necessity of again renapping the nap of the cover. My operation not only makes a better wearing cover, but saves the expense of this step of vulcanization. Covers can be attached to balls by my method much faster and more accurately and at less expense than can be done by hand, as has been

the practice heretofore. Reference is made to my divisional applications filed June 7, 1946, Ser. No. 675,052, now abandoned, for claims on the covered ball and Ser. No. 675,053, for claims on the apparatus, herein illustrated and described.

I claim:

1. The method of securing covers on a gas inflated resilient ball having an internal pressure greater than atmospheric pressure, comprising securing a part only of the surface of a cover to the ball leaving a portion of the cover adjacent the edge thereof spaced from the ball, thereafter seating the ball in a mold, and expanding the ball by exhausting the air from the space between the ball and the wall of the mold cavity to below atmospheric pressure to thereby force all regions of the cover into intimate contact with the ball.

2. The method of securing covers on a gas inflated resilient ball having an internal pressure greater than atmospheric pressure, comprising securing part only of the surface of a cover to the ball, seating the ball in a mold having a cavity larger than the covered ball, reducing the air pressure between the wall of the cavity and the ball to below atmospheric pressure to cause the ball to expand and squeeze the cover between the wall of the ball and the mold.

3. The method of securing a pair of substantially 8-shaped cover members on a gas inflated resilient ball having an internal pressure greater than atmospheric pressure, comprising securing part of the surface of a cover to the ball leaving a portion of the cover adjacent the edge thereof spaced from the ball with an interposed layer of cement, thereafter seating the ball in a mold having a cavity larger than the covered ball, and expanding the ball by exhausting the air from the space between the ball and the wall of the mold cavity to below atmospheric pressure and thereby squeeze the cover members between the wall of the ball and the mold.

4. The method of securing a pair of substantially 8-shaped cover members on a gas inflated resilient ball, comprising preliminarily securing the cover members to the ball on narrow equatorial zones at right angles to each other while leaving the remainder of the cover members spaced from but over-laying the surface of the ball, seating the ball in a mold cavity of sufficient size to readily receive the preliminarily covered ball without disturbing the relation of the cover to the ball, expanding the ball and removing the air from between the cover members and the ball by exhausting the air from the space between the ball and the wall of the mold cavity to below atmospheric pressure to cause all portions of the cover to be squeezed between the wall of the mold and the ball thereby affixing the cover to the ball, and subsequently restoring atmospheric pressure to the exterior of the ball to shrink the covered ball to its normal size.

5. The method of securing a cover on a gas inflated resilient ball, comprising preliminarily securing a part only of the surface of a cover to the ball while leaving the major portion of the cover spaced from but overlaying the surface of the ball, seating the ball in a mold cavity of sufficient size to readily receive the preliminarily covered ball without materially disturbing the relation of the cover to the ball, expanding the ball by exhausting the air from the space between the ball and the wall of the mold cavity to below atmospheric pressure to cause all portions of the cover to be squeezed between the wall of the mold and the ball thereby affixing the

cover to the ball, and subsequently restoring atmospheric pressure to the exterior of the ball to shrink the covered ball to its normal size.

6. The method of securing covers on a gas inflated expandible ball having an internal pressure greater than atmospheric pressure, comprising securing a part only of the surface of a cover to the ball, seating the ball in a mold cavity having a yielding lining which when drawn into contact with the wall of the mold cavity has a larger diameter than the covered ball, exhausting the air from between the lining and the mold and from between the ball and the lining to cause the ball to expand into contact with the lining as a result of internal pressure in the ball, and thereafter applying fluid pressure between the lining and the wall of the mold to increase the pressure between the lining and the ball.

7. The method of securing a pair of 8-shaped cover members on a gas inflated resilient ball having an internal pressure greater than atmospheric pressure, comprising preliminarily securing a part only of the surface of a cover member to the ball with an intermediate layer of cement, seating the ball in a substantially spherical mold cavity having a yielding lining which when drawn into contact with the wall of the mold cavity has an internal diameter of sufficient size to receive the preliminarily covered ball without disturbing the relation of the cover members to the ball, expanding the ball by exhausting the air from between the lining and the mold and from between the ball and the lining, and thereafter applying fluid pressure between the lining and the wall of the mold to increase the pressure between the lining and the ball to squeeze the ball back to its original size carrying the cover with it.

8. The method of applying shrinkable fabric cover members to inflated expandible ball members to provide a tennis ball, comprising forming cover members having a surface area larger than the surface area of the ball member to be covered, coating one of said members with an air curable cement, reducing the pressure around the exterior of the ball to sub-atmospheric to cause the ball to expand, pressing the cover on the ball while so expanded, and thereafter relieving the sub-atmospheric pressure to cause the ball and cover to simultaneously shrink to their normal state.

9. The method of applying a pair of 8-shaped shrinkable fabric cover members to an inflated expandible ball member to provide a tennis ball, comprising forming cover members having a surface area larger than the surface area of the ball member to be covered, coating one of said members with an air curable cement, preliminarily attaching the cover members to the ball by securing a part only of the cover members thereto, placing the preliminarily covered ball in a mold having a substantially spherical mold cavity of a diameter larger than the preliminarily covered ball, reducing the pressure between the wall of the cavity and the ball to sub-atmospheric to cause the ball to expand and press the cover between the ball and the mold cavity while the ball is expanded, and thereafter relieving the sub-atmospheric pressure to cause the ball and cover to simultaneously shrink to their normal state.
